A. L. KRAUS,
BUFFING MACHINE,
APPLICATION FILED OCT. 26, 1915.

Patented Oct. 10, 1916.

2 SHEETS—SHEET 2.

UNITED STATES PATENT OFFICE.

ALBERT L. KRAUS, OF PEABODY, MASSACHUSETTS, ASSIGNOR TO ALBERT L. KRAUS, OF PEABODY, MASSACHUSETTS, AND EDWARD L. MILLETT, OF BEVERLY, MASSACHUSETTS, COPARTNERS DOING BUSINESS UNDER THE FIRM-NAME AND STYLE OF KRAUS MILLETT & COMPANY, OF PEABODY, MASSACHUSETTS.

BUFFING-MACHINE.

1,200,624.

Specification of Letters Patent.

Patented Oct. 10, 1916.

Application filed October 26, 1915. Serial No. 58,029.

To all whom it may concern:

Be it known that I, ALBERT L. KRAUS, a citizen of the United States, and resident of Peabody, in the county of Essex and State 5 of Massachusetts, have invented new and useful Improvements in Buffing-Machines, of which the following is a specification.

My invention relates to buffing machines, and more particularly to the wheels of such 10 machines of the type which carry a removable buffing strip. In the wheels of this type heretofore provided, with which I am familiar, it is necessary to remove a part or parts of the wheel in order to take off the worn-out strip and to replace such part or parts 15 after the new strip has been placed in position. This work of changing or renewing the buffing strip is often laborious, consuming considerable time, and it is one of the 20 objects of this invention to provide a wheel wherein the buffing strip can be readily removed and replaced without removal or replacement of any part or parts of the wheel.

A further object of my invention is to 25 provide means for moistening the buffing strip with a solvent of the finish of the article being operated upon and maintaining the strip in a moistened condition during the operation of the machine, thereby lessening or 30 preventing damage to the finish of the article by reason of the abrasive character of the buffing material.

Referring to the drawings which illustrate an embodiment of my invention,—Fig. 1 is a front elevation of a buffing machine embodying my invention; Fig. 2 is an end view thereof; Fig. 3 is a side view on enlarged scale of my improved wheel; Fig. 4 is a vertical central section through the 40 wheel shown in Fig. 3; and Fig. 5 is a section on line 5—5, Fig. 3.

My improved wheel consists of a felly F made in two sections hinged at 1, and has a hub 2 provided with a spoke 3 preferably 45 formed integral therewith and with one section of the felly F as shown. The said hub is further provided opposite said spoke 3 with a feather 4 adapted to fit within a recess 5 in the spoke 6. The said spoke 6, 50 which is formed integral with the other section of the felly F, is provided with forks 7 extending on opposite sides of the hub 2, and to the ends of said forks there is secured

in any suitable manner, as by screws 8, a cap 9 having a slot 10 (Fig. 5) through which the spoke 3 passes. On opposite sides of said slot 10 are sockets 11 adapted to receive springs 12. One end of each of said springs engages the bottom of its socket 11 and its opposite end engages the hub 2 so that said 60 springs are held under compression between said cap 9 and said hub.

The rim 13 (Fig. 4) is preferably formed integrally with the felly F, and the rim 14 is detachably secured thereto as by the screw 65 15. Each of said rims has a circumferential rib 16 adapted to fit within grooves provided for that purpose in the strip support 17, which is preferably made of felt or other yielding material, and is removably secured 70 between said rims 13 and 14. Mounted in the free end of one section of said felly is a pin 18 adapted to pass through the end of the buffing strip 19 into a socket 20 in the other section of said felly when the wheel 75 is in normal closed position shown in the drawings.

The springs 12 exerting their pressure against the hub 2 and the cap 9, which is fast to the spoke 6, hold the two sections of the wheel yieldingly yet firmly together. When it becomes necessary to replace the strip 19 the two sections are swung apart on their hinge 1 until the pin 18 is out of its socket 20, and while the sections are thus 85 held in open position, the old strip 19 can be readily removed and a new strip substituted therefor. The opening movement of the wheel sections compresses or closes the springs 12, so that when the new strip has 90 been placed in position and the sections are released, the springs are free to expand and return the sections to normal closed position with the buffing strip 19 firmly gripped between their free ends. 95

Mounted on the frame of the buffing machine and preferably below the buffing wheel, is a bracket (Fig. 2) having a horizontal arm 21 and a vertical arm 22, to which is adjustably secured, as by bolts 23, 100 an upright 24 on which is mounted a reservoir or receptacle 25. Preferably the said arm 21 is adjustably secured to a supporting member 21^a of the frame, as by a set screw, so that said reservoir 25 is adjustable both 105 vertically and horizontally with relation to

the buffing wheel. The said reservoir 25 has a cock 26 provided with a dropper 27, and is further provided with a support 28 having vertical walls 29 between which is mounted a trough 30 having apertures 31 at or near its bottom. Below said trough 30 and resting on said support 28 is a moistening pad 32, of felt or the like, held in engagement with the buffing strip 19 by a spring 33 fast on said trough. Preferably a screen 34 is mounted on the bottom of the reservoir 25 and normally held in engagement with the buffing wheel by a spring 35 adjustably secured to the upright 24.

15 When the work being operated upon, as for example, patent leather, has a finish likely to be scratched or otherwise damaged by the abrasive character of the buffing material, the reservoir 25 is filled with any of 20 the well-known liquid solvents of patent leather finish, and such solvent drops from the dropper 27 into the trough 30, moistening the pad 32 which is yieldingly held in engagement with the buffing strip 19, so that 25 said strip becomes moistened with said solvent and is retained in this condition during the buffing operation. The moistened strip softens the finishing of the leather so that the polishing is accomplished while the 30 finish is relatively soft, and thus the likelihood of scratching is lessened if not indeed wholly eliminated.

I claim:

- 35 1. In apparatus for buffing and polishing a coated surface, the combination with a buffing wheel, of means to apply thereto a solvent of the coating to be acted upon comprising a reservoir for said solvent, and a moistener in permanent yielding engagement with said wheel.
- 40 2. In apparatus for buffing and polishing

Copies of this patent may be obtained for five cents each, by addressing the "Commissioner of Patents, Washington, D. C."

a coated surface, the combination with a buffing wheel, of means to apply thereto a solvent of the coating to be acted upon comprising a reservoir for said solvent having 45 a dropper and a moistener located below said dropper and in permanent yielding engagement with said wheel.

3. A buffing machine comprising a buffing wheel, and means to moisten the periphery 50 thereof comprising a reservoir having a dropper, a trough located below said dropper and having an aperture, and a pad below said trough adapted yieldingly to engage said periphery.

4. In apparatus for buffing and polishing a coated surface, the combination with a buffing wheel, of means to apply thereto a solvent of the coating to be acted upon, comprising a reservoir adjustably mounted 60 with relation to said wheel, and having a dropper, a perforated receptacle located below said dropper, a moistening pad located below said receptacle and yieldingly held in engagement with said wheel.

5. In apparatus for buffing and polishing a coated surface, the combination with a buffing wheel, of means to apply thereto a solvent of the coating to be acted upon comprising a reservoir adjustably mounted with 70 relation to said wheel and having a dropper, a perforated trough located below said dropper, a support for said trough fast on said reservoir, a moistening pad located below said trough, and a spring fast on said 75 trough and engaging said pad.

Signed by me at Peabody, Massachusetts, this 23rd day of October, 1915.

ALBERT L. KRAUS.
